(57) **CLAIM**

The ornamental design for a logging tool, as shown and described.

DESCRIPTION

FIG. 1 is a front perspective view of a logging tool showing my new design;

FIG. 2 is a plan view of the embodiment of FIG. 1.

FIG. 3 is a side view of the embodiment of FIG. 1, with the other side being a mirror image thereof.

FIG. 4 is a bottom view of the embodiment of FIG. 1.

FIG. 5 is a front, tip-end view of the embodiment of FIG. 1; while

FIG. 6 is a rear, handle-end view of the embodiment of FIG. 1.

FIG. 7 is a front perspective view of a second embodiment of the design shown in FIG. 1;

FIG. 8 is a plan view of the embodiment of FIG. 7.

FIG. 9 is a side view of the embodiment of FIG. 7, with the other side being a mirror image thereof.

FIG. 10 is a bottom view of the embodiment of FIG. 7.

FIG. 11 is a front, tip-end view of the embodiment of FIG. 7; while; and,

FIG. 12 is a rear, handle-end view of the embodiment of FIG. 7.

The shading on the main shaft of the logging tool represents the color blue and the contrasting shading on the handle represents the color black.
